UNITED STATES PATENT OFFICE.

CHARLES H. JONES, OF TEMPE, ARIZONA TERRITORY.

WATER-BANDAGE.

SPECIFICATION forming part of Letters Patent No. 691,270, dated January 14, 1902.

Application filed October 14, 1901. Serial No. 78,657. (No model.)

To all whom it may concern:

Be it known that I, CHARLES H. JONES, a citizen of the United States, and a resident of Tempe, in the county of Maricopa and Territory of Arizona, have invented a new and useful Improvement in Water-Bandages, of which the following is a specification.

My invention relates to water-bandages for reducing fever in which cold water or other suitable liquid is made to circulate through coils of rubber or other suitable material placed around or in contact with the body the temperature of which is to be lowered; and its objects are, first, to provide a light portable stand for the receptacles of the water or other liquid, whereby its flow through the coil may be adjusted as desired, and, second, to improve in certain particulars such coils. The manner in which I accomplish these objects and others of like character will be more particularly described in this specification, taken in connection with the accompanying drawings, forming a part hereof, and then pointed out in the claims at the end of the description.

In the drawings, Figure 1 is a side view in perspective of the entire apparatus, one of the fluid-receptacles being shown in section. Fig. 2 is a view from above of the base of the stand. Fig. 3 is a side view of the base of the stand. Fig. 4 is a view in section showing the manner in which the movable beam is pivoted and adjusted on the upright of the stand. Fig. 5 represents cross-sections of different forms of the tube used in the coil. Fig. 6 is a longitudinal section of the tube at the junction with the coil.

Similar letters of reference refer to similar parts throughout the several views.

40 A is an upright bar or tube of iron, wood, or other material, preferably an iron tube, flattened at the upper end and notched at its extremity. The beam B, which may be of any material, is pivoted on the tube A by 45 means of the pin D, which fits loosely in the notches at the end of A. This permits B to swing freely on D, which is placed at its center. To the beam B is also attached the semi-circular piece of metal or other suitable material C, which as B swings up and down on D passes freely from end to end between the

upper part of the upright A and the projecting upturned flange F, which is made or fastened onto A and through which works the rat-tail screw E, by means of the friction of 55 which against C the beam B can be readily adjusted in any desired position, the ends being at the same elevation or either one at any desired height above the other.

Upon the ends of the beam B are made or 60 placed hooks, to which are attached buckets K and L, in which is placed the water or other liquid. These buckets are preferably made, as shown in Fig. 1, with an outer and inner chamber, the outer to be packed with 65 sawdust or other non-heat-conducting substance M and the inner filled with ice and water or other liquid. At the base of each bucket, by means of a pipe and cock O, the water may be drawn off into the tube P, of 70 rubber or other suitable material. Over the inner end of the outlet-pipe from the buckets may be placed wire screens V, which will prevent any solid passing into the tube and coil. The tube P, which may be of any desired length, runs from one bucket to the coil 75 S and thence to the other bucket. The coil S, which is part of the tube, may be made in any form and may be adapted to be wound around or placed in contact with any part of 80 the body. Where it comes in contact with the body, the temperature of the body is lowered by the flow of cold water or other liquid through the coil. When all of the liquid has passed from one receptacle to the other, the 85 beam B may be swung up, so that the full receptacle is on a higher level than the empty one, thus causing the liquid to flow back again, and so on.

In order to prevent the tube from bending, 90 so as to stop the flow, and in order that it may be more easily handled, it may be passed through a Y-shaped tube of metal or other material Q, which may be adjusted as desired, thus holding together the two parts of 95 the tube running from the coil. Another device that may be used for the same purpose to prevent kinking of the tube is to have the part of the tube where it leaves the coil, as shown at T, Fig. 1, fastened to the coil, so 100 that both parts of the tube will be rigidly attached at T and both leave the coil at the

same place, thus lessening the chance of the tube being bent, so that water will not flow through it.

To further prevent kinking of the tube, it 5 may at the point T, where it leaves the coil and is apt to bend, be reinforced by being thickened, as shown in Fig. 6.

The tube of which the coil is constructed 10 may be flattened and made thin on the side which comes in contact with the body, as shown in Figs. 5 and 6, thus presenting a larger cooling-surface and a thinner wall between the cooling liquid and the body.

It will be observed that the apparatus 15 described is of light and durable construction and is adapted to be knocked down, packed in small compass, and readily set up again. I have also provided a base for the stand, which is of the same simple construction.

20 The upright A is notched at its base, the notch fitting over the thin plate G, made of metal or other suitable material and having a foot at either end. To G are attached, by thumb-screws H, which set in notches on the upper 25 edge of G, the plates J and J', which are of the same construction as G, each having a foot at its end and which fit tightly around the upright A. By putting the parts together and adjusting the thumb-screws H the base 30 is held firmly in place and the apparatus is supported. In this way a portable and simply-constructed device is produced which can be quickly adjusted at a bed side, permitting cold water or other liquid to be steadily and 35 continuously applied to any part of the body of a patient.

Having now described my invention, what I claim as new, and desire to secure by Letters Patent of the United States, is—

40 1. In a water-bandage and adjusting apparatus therefor, the combination of an upright supporting adjustably thereon a vertically-swinging beam, adapted to hold liquid-receptacles at each end of the beam, a flexible tube 45 leading from one receptacle to a coil and thence to the other receptacle, substantially as described.

2. In a water-bandage and adjusting apparatus therefor, the combination of an upright, 50 a base to support the same, a beam pivoted on the upright and adapted to swing vertically and be adjusted thereon, liquid-holding receptacles at each end of the beam, a flexible tube leading from one receptacle to a 55 coil and thence to the other receptacle, substantially as described.

3. In a water-bandage and adjusting apparatus therefor, the combination of an upright, a base to support the same, a beam pivoted on the upright and adapted to swing vertically and be adjusted thereon, liquid-holding receptacles at each end of the beam, a flexible tube leading from one receptacle to a coil, the tubing of which is flat and thin on one side, and thence to the other, substantially as de- 60 65 scribed.

4. In a water-bandage and adjusting apparatus therefor, the combination of an upright, a base to support the same, a beam pivoted on the upright and adapted to swing vertically and be adjusted thereon, liquid-holding receptacles at each end of the beam, a flexible tube leading from one receptacle to a coil, the tubing of which is made flat and thin on one side, and thence from the coil to the other 70 75 receptacle; the parts of the tubing where they leave the coil being rigidly attached thereto and adapted to leave it at the same place and be joined together for a short distance, substantially as described.

5. In a water-bandage and apparatus therefor, the combination of an upright, a base to support the same, a beam pivoted on the upright and adapted to swing vertically and be adjusted thereon, liquid-holding receptacles 80 85 at each end of the beam, a flexible tube leading from one receptacle to a coil, the tubing of which is made flat and thin on one side, and thence from the coil to the other receptacle; the parts of the tubing where they leave the coil being rigidly attached thereto and adapted to leave it at the same place and to be there reinforced by thickening, to prevent 90 95 kinking and to facilitate handling of the tube, substantially as described.

6. A coil of tubing adapted to be applied to the human body to reduce the temperature thereof by means of cold liquid flowing through the said coil; the tubing of said coil being flattened and thinned at the points 100 where it comes in contact with the body, to present a larger cooling-surface and a thinner wall between the cooling liquid and the body, substantially as described.

In testimony whereof I have hereunto set 105 my hand in the presence of two subscribing witnesses.

CHARLES H. JONES.
